UNITED STATES PATENT OFFICE.

FRED C. HANSEL, OF KANSAS CITY, MISSOURI.

DESIGN FOR A LAMP-BOX.

47,848.

Specification for Design.

Patented Sept. 21, 1915.

Application filed April 3, 1915. Serial No. 19,080. Term of patent 14 years.

To all whom it may concern:

Be it known that I, FRED C. HANSEL, a citizen of the United States, residing at Kansas City, in the county of Jackson and State of Missouri, have invented a new, original, and ornamental Design for Lamp-Boxes, of which the following is a specification, reference being had to the accompanying drawing, forming a part thereof.

The figure is a perspective view of a lamp box, showing my new design.

I claim:

The ornamental design for a lamp box, as shown.

FRED C. HANSEL.

Witnesses:

PERRY HOLLOWAY,
LEON GOLDEN.
